GAME

Application filed November 4, 1930. Serial No. 493,367.

This invention relates to games and has more particular reference to a game apparatus in which a projectile is projected by fluid pressure at a target.

The invention broadly comprehends a game apparatus including a game board having an upper surface upon which one or more targets are arranged and a pneumatic or fluid pressure actuated projectile adapted for projection at the target.

More specifically the invention contemplates a game apparatus in which use is made of a game board having an upper surface provided with one or more targets and in which a pneumatic or fluid pressure actuated diaphragm is employed for projecting a projectile at the target.

Other objects of the invention reside in the provision of a game apparatus which is comparatively simple in its construction and mode of use, inexpensive to manufacture, and which is highly attractive and amusing to the participants.

With the above recited and other objects in view reference is had to the following specification and accompanying drawings in which there is exhibited one example or embodiment of the invention, while the claims define the actual scope of the same.

In the drawings—

Figure 1 is a perspective view of the game illustrating the manner in which the same is played.

Fig. 2 is an enlarged sectional view therethrough taken approximately on the line 2—2 of Fig. 1.

Fig. 3 is a similar view illustrating the flexed condition of the diaphragm.

Referring to the drawings by characters of reference, 10 designates a game board of any desired configuration which is provided with an upper surface 11 having one or more targets 12 illustrated in the present instance as pegs although equivalent targets such as recesses or designated areas may be employed. The game further includes one or more projectiles 13 which in the present instance are indicated as rings adapted to engage over the pegs or pins 12.

50 The means for projecting the projectiles

13 toward the targets 12 is of the fluid pressure operated type and in the present instance said means consists of a fluid chamber 14 which is defined by a recess which opens through the upper surface 11 of the game board and which is covered at the upper open end by a flexible wall or diaphragm 15 which is normally shaped to bulge downwardly within the fluid chamber as illustrated in Figs. 1 and 2 of the drawings. Suitable means is provided for introducing a fluid pressure to the fluid chamber 14 and as illustrated this means consists of a bulb 16 from which a tube 17 leads, the tube being inserted in the outer end of the fluid passage 18 which leads from the fluid chamber 14 to the outer edge of the game board 10. In practice a plurality of said fluid passages and a plurality of bulbs and tubes may be employed. In event only one player is using the game a stopper 19 may be inserted in the outer end of the fluid passage or passages 18 which are not in use, as illustrated in Fig. 3 of the drawings.

In use the projectile 13 is positioned on the flexible wall or diaphragm 15 and sighted toward the target which is the objective. The player then squeezes the bulb 16 to introduce a fluid pressure to the fluid chamber 14 for the purpose of flexing the diaphragm from the normal position illustrated in Fig. 2, to the position illustrated in Fig. 3. Obviously this projects the projectile 13 toward the objective target.

While there has been illustrated and described a single and preferred embodiment of the invention, it is to be clearly understood that no limitation is necessarily made to the precise structural details, and the right is reserved to other embodiments thereof which properly fall within the scope of the appended claims.

What is claimed is:

1. A game having the combination of a game board, a target on the upper surface thereof, a projectile and fluid pressure operated means for projecting the projectile upwardly over the board and at said target, said projecting means consisting of a closed fluid receiving chamber having a flexible up-

per wall and means for introducing fluid under pressure to said chamber to flex said wall for projecting therefrom, a projectile rested thereon.

- 5 2. A game including a projectile, a game board having an upper surface provided with a target defined thereon, said board having a recessed portion opening through the upper surface thereof, a flexible diaphragm element covering the upper open end of the recess and defining therewith a closed fluid chamber and means for introducing a fluid under pressure to said fluid chamber for flexing said diaphragm to project therefrom and at the target, a projectile rested on said diaphragm element.
- 10 3. A game apparatus comprising a game board having an upper surface provided with a target, a recessed portion of said board opening through the upper surface thereof, a flexible diaphragm element covering the upper open end of the recess and normally bulged downwardly and defining with said recess a closed fluid chamber, said game board having a passageway leading from the recess to the outer edge thereof and means for introducing a fluid pressure through said passageway to the recess for flexing said diaphragm whereby to project therefrom and at the target, a projectile rested upon said diaphragm.
